UNITED STATES PATENT OFFICE

157,544

PERFUME BOTTLE

James Teague, Chicago, Ill., assignor to Dana Perfumes, Inc., Chicago, Ill., a corporation of Illinois

Application March 5, 1949, Serial No. 1,248

Term of patent 14 years

(Cl. D58—8)

To all whom it may concern:

Be it known that I, James Teague, a citizen of the United States of America, residing at Chicago, in the county of Cook, State of Illinois, have invented a new, original, and ornamental Design for Perfume Bottle, of which the following is a specification, reference being made to the accompanying drawings, forming part thereof.

Referring to the drawings, Fig. 1 is a top plan view of a perfume bottle embodying my new design; Fig. 2 is a bottom plan view; Fig. 3 is a front elevational view and Fig. 4 is a side elevational view of the same.

I claim:

The ornamental design for a perfume bottle, substantially as shown.

JAMES TEAGUE.
